UNITED STATES PATENT OFFICE.

ALFRED TROSCH, OF ROCHESTER, NEW YORK, ASSIGNOR TO ARTHUR H. INGLE, OF ROCHESTER, NEW YORK.

POWER TRAVERSE AND FEED MECHANISM FOR PLANERS.

Application filed March 6, 1920. Serial No. 363,765.

To all whom it may concern:

Be it known that I, ALFRED TROSCH, a citizen of the United States, and resident of Rochester, county of Monroe, State of New York, have invented an Improvement in Power Traverse and Feed Mechanism for Planers, of which the following description, in connection with the accompanying drawings, is a specification, like characters on the drawings representing like parts in each of the several views.

This invention relates to metal working planers and more particularly to an improved arrangement and disposition of power connections for operating the tool heads on the crossrail and on the side uprights whereby these may be moved rapidly for traversing the same to or from an operative position, or operated at relatively slow rates by other connections for the feed movement thereof in the operation of the machine. A principal object of the invention is to provide a relatively simple, compact, and reliable system of connections for the distribution of power whereby either the feed or the rapid traverse for any tool head may be instantly thrown into or out of engagement, the arrangement being such that there is no possibility of the feed and rapid traverse being both engaged at the same time, and the controlling elements being located in convenient position for manipulation by the operator. The foregoing and other objects and advantages of the invention will more fully appear from the following detailed description, and the distinctive features of novelty will thereafter be pointed out in the appended claims.

Referring to the drawings:

Fig. 1 is a partial front view with portions broken away and in section showing one end of a planer equipped with the invention;

Fig. 2 is a partial side view thereof with portions broken away;

Fig. 3 is a sectional detail on line 3—3 of Fig. 2;

Fig. 4 is a sectional detail on line 4—4 of Fig. 2; and,

Fig. 5 is a fragmentary section on line 5—5 of Fig. 1.

10 indicates a planer bed on which is fitted a usual reciprocating table 11. 12 are the side uprights only one thereof being shown at one side of the machine, these be-

ing joined by the usual top rail 120 to constitute the upright housing on which the crossrail 140 and the tool heads are mounted for adjustments and operative movements. 13 indicates a motor mounted on the top rail 120, this motor being of a reversible type or adapted through reversing gearing to drive a shaft 14 horizontally journaled at the top of the housing, in either direction.

The shaft 14 through bevel gearing 15 drives a shaft 16 which is vertically journaled to extend downward alongside of the upright 12. This shaft is formed with a keyway 16^a extending through the major intermediate portion of the length thereof. Slidably keyed on the shaft 16 is a bevel pinion 17 which drives a bevel pinion 18 fixed on a short shaft 19 journaled in a bearing bracket 20 borne by the crossrail. The pinion 17 is also journaled in this bracket so as to move vertically with the crossrail while being driven in all its vertical positions by the shaft 16. The shaft 19 has loosely fitted thereon a pinion 21 which is engaged with a gear 22 loosely mounted on a bearing shaft 23 borne by the crossrail. The gear 22 is adapted to operate the crossrail screws 24 or the crossrail shaft 25 selectively by means of the click box pinions 26 in usual manner. The shaft 19 has slidably keyed thereon a clutch hub 27 which is adapted to engage a co-operative clutch face on the pinion 21 and upon moving this clutch hub to thus make the pinion 21 fast to the shaft 19 rapid traverse movement will be transmitted through the described connections from the motor 13 in either direction to a selected feed screw or shaft of the crossrail. 28 indicates a feed box at the base of the machine which may be of usual type and actuated in usual manner by the table driving connections. This feed box through a pitman 29 operates a segmental gear 30 journaled in a bracket 31 at the base of the machine and having a lateral projecting arm 30^a with which the pitman 29 is directly engaged. The gear segment 30 meshes with a pinion 32 fixed at the lower end of a shaft 33 vertically journaled alongside the upright. The shaft 33 has a keyway extending the major portion of the length thereof. To this shaft is slidably keyed a pinion 34 journaled and held from endwise movement in a bearing lug 20^a of

110

the bearing bracket 20 borne by the cross-rail. The pinion 34 meshes with a pinion 35 fixed on a short shaft journaled in the bracket 20 and having fixed at its outer end 5 a feed plate 36. This feed plate is slotted radially of said shaft as indicated at 36^a and in this slot is adjustably fitted a crank pin 37 at the end of a pitman 38. The pitman 38 has its other end engaged with a lever 39 which has a hub 39^a journaled on a sleeve extension 22^a of the gear 22. Slidably keyed on the sleeve extension 22^a is a clutch hub 40 and the lever hub 39^a is equipped with a clutch face adapted to be engaged by said clutch hub when it is moved inward, to thus 10 make fast the lever 39 to the gear 22. When this clutch connection is made therefore, feed movement will be imparted from the feed box 28 to a selected feed screw or shaft 15 24, 25. The clutch hubs 27, 40, have grooved necks 27^a which are engaged by pins or rolls borne by a shifter lever 41, this lever having an intermediate pivot or fulcrum 42 between these clutch hubs and having a handle 25 41^a extending downward for convenient actuation. With this intermediate fulcrum of the lever it will be understood that when one of the clutch hubs is in, the other is necessarily out, while in an intermediate position both clutch hubs are disengaged. For 30 imparting rapid traverse movement to the side tool head which is mounted on the upright 12, the shaft 16 has fixed at the lower end thereof a bevel pinion 43 which meshes 35 with a bevel 44 fixed on a short shaft 45 journaled in a lateral bracket extension 46^a of a side tool head 46 which is fitted to slide on the upright 12. The shaft 45 has loosely mounted thereon a pinion 47 equipped with 40 a clutch face at one side thereof which is engageable by a clutch hub 48 slidably keyed on the shaft 45. The pinion 47 meshes with a gear 49 mounted on a bearing shaft 50 and having a sleeve 49^a extending therefrom. 45 When the pinion 47 is made fast to the shaft 45 by the clutch described, rapid traverse movement will be transmitted to the gear 49 and thence to a pinion 51 fixed at one end 50 of a shaft 52, this shaft being horizontally journaled in an extension of the side tool head 46 and having fixed at its inner end a spiral gear 53 which drives a vertical spiral gear 54. The gear 54 is held from endwise movement between lugs 55 of the tool head 55 and it has a threaded passage therethrough so as to constitute a nut engaging a stationary screw 56 extending vertically in the upright 12 and fixed at its lower end in the base of the machine as indicated at 56^a. 60 Thus the rapid traverse movement as described, imparted to the nut 54 effects a raising and lowering of the tool head 46. For imparting feed movement to the tool head 46 the shaft 33 has slidably keyed thereon 65 a bevel pinion 57 which is mounted in the side head bracket 46^a for movement therewith. The pinion 57 engages a pinion 58 fixed to a short shaft journaled in the bracket 46^a and having fixed at its outer end a slotted feed plate 59. This feed plate 70 has adjustably engaged in the slot thereof a crank pin 60 at one end of a pitman 61, the other end of which engages an arm 62 which has a sleeve hub 62^a loosely mounted on the sleeve extension 49^a with a clutch face 75 formed thereon. This clutch face is engageable by a clutch hub 63 slidably keyed on the sleeve 49^a and thereby the arm 62 may be made fast to the gear 49 by shifting said clutch hub into operative engagement. This 80 operative engagement thus connects the feed movement to the side tool head.

The clutch hubs 48, 63, are engaged by a shifter lever 64 pivoted at 65 to the tool head extension at an intermediate point between 85 these hubs. This lever is equipped with a handle 64^a and may be manipulated similarly as the lever 41 to engage either the rapid traverse or the feed, or to disconnect both in an intermediate position as seen in 90 Fig. 1. Thus either a variable feed or a rapid traverse movement may be engaged with the feed screws and rods for operating the tool heads on the crossrail, or with the side tool head, as may be required, and the 95 levers for controlling these connections are arranged in most convenient position for control by the operator at the side of the machine and adjacent each other. I am aware that the invention may be embodied in other 100 specific forms without departing from the spirit or essential attributes thereof, and I therefore desire the present embodiment to be considered in all respects as illustrative and not restrictive, reference being had to 105 the appended claims rather than to the foregoing description to indicate the scope of the invention.

Having described my invention what I claim as new and desire to secure by Letters 110 Patent is:

1. A planer, comprising a crossrail equipped with means for moving a tool head thereon, a rapid traverse connection to said tool head moving means including a shaft 115 extending vertically alongside one of the planer uprights, a connection for imparting relatively slower feed movement to such tool head including another shaft extending vertically alongside a planer upright, and means 120 for selectively engaging said shafts with the tool head moving means, said engaging means for the two shafts being interconnected whereby only one of them may be engaged at the same time.

2. A planer, comprising a crossrail equipped with means for moving a tool head thereon, rapid traverse connections for operating said tool head including a keyed shaft 125 extending vertically of the machine 130

housing, connections for imparting a relatively slower feed movement to the tool head including another shaft extending vertically of the housing, and interconnected clutch members for selectively engaging said shafts with the tool head moving means whereby either the rapid traverse or the feed movement may be engaged therewith, or both disconnected at will.

10 3. A planer, comprising a crossrail equipped with means for moving a tool head thereon, and also having a side tool head movable on a planer upright, rapid traverse connections for such tool heads including a vertically extending shaft, separate feed connections for such tool heads including another vertically extending shaft, and interconnected clutches arranged for selectively engaging either the rapid traverse or the

15 feed movement with a tool head either on said crossrail or on an upright at will.

4. A planer, comprising a crossrail equipped with a plurality of tool head operating shafts, a gear at the end of the cross-
20 rail selectively engageable with said shafts, rapid traverse connections to said gear including a disconnecting clutch, separate feed connections to said gear including a disconnecting clutch, and a connection between

25

said clutches whereby only one of them may be moved into operative position at the same time.

5. A planer, comprising a crossrail equipped with a plurality of tool head operating shafts, a gear at the end of the cross-
30 rail selectively engageable with said shafts, rapid traverse connections to said gear including a vertical shaft and a disconnecting clutch, separate feed connections to said gear including another vertical shaft and another disconnecting clutch, said latter clutch mounted on a sleeve of said gear, and said clutches being interconnected whereby only one of them may be engaged at the same time.

45 6. A planer, comprising a side tool head mounted on one of the planer uprights, a stationary screw associated with such upright and secured to the bed of the machine, a nut fitting said screw borne by said tool 50 head, rapid traverse connections to said nut including a disconnecting clutch and separate feed connections thereto also including a disconnecting clutch.

In testimony whereof, I have signed my 55 name to this specification.

ALFRED TROSCH.
